UNITED STATES PATENT OFFICE.

HENRY L. LEIBE, OF NEWARK, NEW JERSEY.

DESIGN FOR A CANE OR UMBRELLA HANDLE.

SPECIFICATION forming part of Design No. 20,745, dated May 19, 1891.

Application filed April 17, 1891. Serial No. 389,379. Term of patent 3½ years.

To all whom it may concern:

Be it known that I, HENRY L. LEIBE, a citizen of the United States, residing at Newark, in the county of Essex and State of New Jersey, have invented and produced a new and original Design for Cane or Umbrella Handles; and I do hereby declare the following to be a full, clear, and exact description of the invention, such as will enable others skilled in the art to which it appertains to make and use the same, reference being had to the accompanying drawing, and to letters of reference marked thereon, which forms a part of this specification.

15 The single figure in the accompanying drawing is deemed sufficient to illustrate the design, the illustration representing a cane or umbrella handle in side elevation.

20 The leading feature of the design consists in a cane or umbrella handle the outer face of which has the shape or configuration of a natural wood stick having the irregularities

of a portion of root or knot, the outside surface of which has a vine-shaped ornament in low relief.

25

A indicates the knot or root like irregularities of a stick and B a vine-shaped ornament in low relief extending around the handle, of which vine-shaped ornament b represents branches or tendrils, a leaves, and c grape-like clusters or bunches.

30 What I claim as new is—

The design for a cane or umbrella handle herein shown and described, the same comprising an irregularly-shaped handle and a 35 vine-shaped ornament in low relief, as set forth.

In testimony that I claim the foregoing I have hereunto set my hand this 27th day of March, 1891.

HENRY L. LEIBE.
